BICYCLE GEAR PROTECTOR

Larry Goldmeier, Great Neck, N.Y.
(200 5th Ave., New York, N.Y. 10010)

Filed Mar. 1, 1968, Ser. No. 10,798

Term of patent 7 years

U.S. Cl. D90—1
Int. Cl. D12—14

FIG. 1 is a side view of the bicycle gear protector as placed on a bicycle.

FIG. 2 is a top view of the bicycle gear protector.

FIGS. 3, 4, and 5 are, respectively, a bottom view, a front end view and back end view of the bicycle gear protector.

The bicycle fragmentarily shown in broken lines in FIGURE 1 is included only for illustrative purposes.

I claim:

The ornamental design for a bicycle gear protector, as shown and described.
